UNITED STATES PATENT OFFICE

152,020

DESIGN FOR A RING OR THE LIKE

Stephen Anthony Reichmuth, St. Louis, Mo.

Application September 12, 1946, Serial No. 133,261

Term of patent 14 years

(CL. D45—10)

To all whom it may concern:

Be it known that the undersigned, Stephen Anthony Reichmuth, a citizen of the United States, residing at St. Louis, Missouri, has invented a new, original, and ornamental Design for a Ring or the like, of which the following is a specification, reference being had to the accompanying drawing, forming a part thereof, in which:

Fig. 1 is a front elevational view of a ring or the like, embodying my new design;

Fig. 2 is an elevational view of one side thereof; and

Fig. 3 is an elevational view of the other side thereof.

The characteristic features of my design for a ring reside in the portions shown in full lines,

I claim:

The ornamental design for a ring or the like, substantially as shown and described.

STEPHEN ANTHONY REICHMUTH.
